Geo. P. Kimmel

ATTORNEY.

UNITED STATES PATENT OFFICE

CHARLES J. STEWART, OF MEADVILLE, PENNSYLVANIA

CASH RECEPACLE

Application filed October 18, 1929. Serial No. 400,634.

This invention relates to a cash receptacle or box for use in connection with the compartments of cash drawers and has for its object to provide, in a manner as hereinafter set forth, a receptacle or box capable of being removably mounted and held stationary within a compartment of a cash drawer to render such compartment to conform to the new size of currency.

10 Further objects of the invention are to provide, in a manner as hereinafter set forth, a removable cash receptacle or box for use in connection with compartment cash drawers for a purpose referred to and which is simple 15 in its construction and arrangement, strong, durable, thoroughly efficient in its use, readily installed with respect to the compartment of a cash drawer, and inexpensive to manufacture.

20 With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope 25 of the claims hereunto appended.

30 In the drawings wherein like reference characters denote corresponding parts throughout the several views:—

Figure 1 is a fragmentary view in top plan of a compartment cash drawer showing the 35 adaptation therewith of a removable cash receptacle or box in accordance with this invention.

Figure 2 is a section on line 2—2, Figure 1.

Figure 3 is a rear elevation of the receptacle or box.

Figure 4 is a section on line 4—4, Figure 1.

Referring to the drawing in detail 1 denotes a cash drawer which is generally set up of a series of compartments, and as illustrated but one compartment is shown and which is provided by the partitions 2, 3 and the sides 4 of the drawer 1.

The cash receptacle or box which is adapted to be removably mounted in the compartment 5 of the cash drawer 1 is of rectangular

contour and includes a bottom 6, a back wall 7, and a pair of side walls 8, 9. The receptacle which is referred to generally at 10 has the front thereof open and when the receptacle is mounted in the compartment 5 the front is closed by a front wall 11 of the compartment 5.

Each side wall is formed of two parts of different heights, and one of said parts is indicated at 12 and the other at 13. The part 12 is of materially greater length than part 13 and the latter is arranged at the rear of part 12 and merges into the back wall 7. The back wall 7 corresponds in height to the height of the part 13 of the side walls and said back wall 7 is of less height than the height of the side walls of the compartment 5.

The parts 12 of the side walls of the receptacle or box are of a height to extend and be flush with the top edges of the side walls of the compartment 5 and formed integral with the top edges of the parts 12 of the side walls of the receptacle or box 10, as well as being co-extensive with said parts 12 are oppositely disposed, angle-shaped flanges. The flange carried by the part 12 of the wall 8 is indicated at 14 and the flange at the top of the part 12 of the wall 9 is indicated at 15.

The flanges 14, 15 are adapted to abut the partition 2 and side wall 4 of drawer 1 when the receptacle or box 10 is mounted in compartment 5.

For the purpose of preventing shifting of the receptacle or box 10 within the compartment 5, the back wall 7 has connected therewith and projecting therefrom a bow-shaped spring 16 having rounded ends 17 which abut against the partition 3 of the drawer 1. The back wall 7 of the receptacle or box 10 is formed with a pair of vertically disposed slots 18 arranged in opposed spaced relation and through which extends the spring 16.

The spring 16 centrally thereof, is offset as at 19 to provide a semi-circular part and said part extends through the slots 18.

The size of the receptacle or box 10 is such as to correspond to the size of the new currency but the box or receptacle 10 is of such

size as to permit the new style of currency to be conveniently positioned therein and removed therefrom.

The spring 16 acts to maintain the forward end of the box or receptacle 10 against the front 11 of the compartment 1 whereby the front of the receptacle or box 10 is closed and further the receptacle is prevented from shifting laterally or lengthwise of the compartment 5. The flanges 14 and 15 act to prevent the transverse shifting of the receptacle or box 10 within compartment 5.

It is thought the many advantages of a removable cash receptacle or box for use in connection with the compartments of a cash drawer and in accordance with this invention can be readily understood, and although the preferred embodiment of the invention is as illustrated and described, yet it is to be understood that changes in the details of construction can be had which fall within the scope of the invention as claimed.

What I claim is:—

1. A removable cash receptacle for the compartments of cash drawers comprising an open top body portion for positioning in and of less length than the length of the compartment, flanges projecting from the top of the sides of said body and abutting the side walls of the compartment, and means projecting from the rear of said body and bearing against the rear wall of the compartment for maintaining the body in abutting engagement with the front wall of the compartment, said body further including an open front.

2. A removable cash receptacle for the compartments of cash drawers comprising an open top and open front body portion for mounting in a compartment and of less length than the length of the latter, means carried by the sides of said body for abutting the side walls of the compartments to prevent the transverse shifting of said body portion relative to said compartments, and means projecting from and carried by the rear of said body portion and engaging the rear wall of the compartment for maintaining the open front of the body portion against the front wall of the compartment.

3. A removable cash receptacle for the compartments of cash drawers comprising an open top and open front body portion having each of its side walls formed at the top thereof with a laterally extending angle-shaped flange, and a resilient element connected to the rear of said body portion and projecting rearwardly therefrom.

4. A removable cash receptacle for the compartments of cash drawers comprising a body portion formed of a back wall, a bottom and a pair of side walls, each of said side walls having its rear part of less height than its forward part, a laterally extending, angle-shaped flange projecting from the top of the

high part of each side wall and co-extensive with said high part, and resilient means anchored to said back wall and projecting rearwardly therefrom.

In testimony whereof, I affix my signature 70 hereto.

CHARLES J. STEWART.
